ATTORNEY

UNITED STATES PATENT OFFICE.

JOSEPH R. CRIST, OF HARDWICK, MINNESOTA.

CLOTHES-RACK.

1,261,363.

Specification of Letters Patent. Patented Apr. 2, 1918.

Application filed September 23, 1916. Serial No. 121,848.

To all whom it may concern:

Be it known that I, JOSEPH R. CRIST, a citizen of the United States, residing at Hardwick, in the county of Rock and State 5 of Minnesota, have invented certain new and useful Improvements in Clothes-Racks, of which the following is a specification.

This invention relates to garment racks, and aims primarily to provide a portable 10 clothes stand capable of being conveniently carried in a trunk, satchel or suit case.

A further object of the invention is to provide a stand of this character which has its trunk or body portion formed of a plurality 15 of sections arranged in such manner as to permit of folding or collapsing the device so as to occupy but a small amount of space. Furthermore, the invention aims to provide improved means for detachably connecting 20 rack members and legs to the said body so that the collapsed stand will form a compact bundle free of projecting elements. A still further object is to provide a device of this character which may be manufactured 25 at extremely low cost, which may be quickly set up or collapsed, and which is equipped with improved locking means for holding the trunk portion of the device rigid when set up.

With these objects in view, together with others which will appear as the description proceeds, the invention resides in the novel formation, combination and arrangement of parts, all as will be described more fully 35 hereinafter, illustrated in the drawings, and particularly pointed out in the claims.

In the drawings:—

Figure 1 is a side elevation of a clothes stand or rack constructed in accordance with 40 the invention, the view showing the same in set up position,

Fig. 2 is an enlarged side elevation of the top portion of the trunk with one of the clothes arms removed,

Fig. 3 is a fragmentary side elevation of 45 one end of one of the clothes arms,

Fig. 4 is a side elevation of a portion of the bottom section of the trunk, and illustrating a socket for securing one of the sup- 50 porting legs thereto,

Fig. 5 is a side elevation showing one end of one of the legs, and

Fig. 6 is a perspective view showing the 55 clothes rack in folded or collapsed state.

Referring now more particularly to the drawings, 7 indicates the bottom or base

section of the stand, and 8 the top section, while 9 and 10 represent respectively the intermediate sections. These sections may be formed either of wood or metal, and are 60 preferably of small dimension in cross section. The various sections of the trunk portion of the rack are of equal length, and are hinged to each other as at 11 in successive order. The hinges 11 connect the adjacent 65 ends of the sections in such manner as will permit of the trunk of the device being folded into the shape illustrated in Fig. 6 of the drawings. Hooks 12 are arranged upon the various sections to hold the same rigidly 70 when the device is in adjusted or set up position, the said hooks being adapted for engagement with the studs 13 on the adjacent section end.

To form a suitable base for the device 75 when extended, and to prevent the stand becoming readily rendered top heavy or unbalanced, legs 14 are provided. These legs are relatively short in length, and are each provided at their ends with beveled faces so as 80 to fit flush against the side of the lowermost section of the stand and upon a floor surface when propped against the trunk. I preferably provide four of these legs, one for each of the four faces of the bottom section. 85 The bottom section has its various sides cut away and covered with metallic plates 15, the said plates having formed therein key-hole slots 16, for the reception of heads 17 formed upon and projecting outwardly from 90 certain of the beveled faces of the leg ends. The arrangement is such that when the legs are properly attached to the base section, the weight of the rack will force the base downwardly until the heads 17 ride into the restricted portions of the key-hole slots 16. This construction forms a rigid connection 95 between the base section and the various legs, so that tilting or overbalancing of the stand is obviated, and so that the legs may be 100 readily detached when it is desired that the device be collapsed.

The various side faces of the uppermost of the trunk sections are also provided with cut out portions, the same being covered by 105 plates 18 having downwardly extending key-hole slots 19 therein, to receive heads 20 projecting outwardly from the extremities of the rack arms 21. The arrangement is such that the weight of the arms forces the heads 110 downwardly into the restricted portions of the key-hole slots, whereby accidental de-

tachment of the arms is prevented. Obviously, the arms may be readily removed when it is desired that the device be collapsed.

- 5 5 From the foregoing it is apparent that I have provided an extremely simple and yet thoroughly practical clothes stand, and one which, when not in use, will occupy but a small amount of space. The device may be 10 very conveniently carried in a trunk or hand grip, and will be readily available at all times for traveling persons.

While the above is a description of the preferred embodiment of the invention, it is 15 apparent that various changes may be made in the various details of the construction, if desired, without departing from the spirit of the invention or exceeding the scope of the claims.

- 20 20 What is claimed is:—

1. A clothes rack comprising a body formed of a plurality of sections rectangular in cross section, hinges connecting the adjacent ends of the said sections, the outer sections being hinged to their adjacent sections 25

so as to swing in the same direction, and the intermediate sections being hinged together at their adjacent ends so as to swing in directions at right angles to the direction of movement of the said outer sections.

2. A clothes rack comprising a body formed of a plurality of sections rectangular in cross section, hinges connecting the adjacent ends of the said sections, the outer sections being hinged to their adjacent sections so as to swing in the same direction, the intermediate sections being hinged together so as to swing at right angles to the direction of movement of the said outer sections, the various sections being of equal 40 length, and hooks on certain of said sections for holding the same engaged with the next adjacent sections.

In testimony whereof I affix my signature in presence of two witnesses.

JOSEPH R. CRIST.
